Inventor Frederick G. Tilley.
by James L. Norwood, Attorney.

UNITED STATES PATENT OFFICE.

FREDERICK CHARLES TILLEY, OF LONDON, ENGLAND.

VAPOR BURNER AND LAMP.

1,360,824.

Specification of Letters Patent. Patented Nov. 30, 1920.

Application filed March 17, 1920. Serial No. 366,524.

To all whom it may concern:

Be it known that I, FREDERICK CHARLES TILLEY, a subject of the King of Great Britain, residing at London, England, have invented certain new and useful Improvements in or Connected with Vapor Burners and Lamps, of which the following is a specification.

This invention relates to improvements in vapor burners of the inverted type employing an incandescent mantle the vapor being obtained from a liquid hydrocarbon such as ordinary petroleum supplied under pressure to the heated burner whence it escapes as vapor through a small orifice, is mixed with the requisite air and burnt on the well known Bunsen principle.

The object of the present invention is to produce a burner in which the parts especially those liable to corrosion or clogging may be easily and cheaply replaced and to construct and dispose them in such manner that they shall be accessible and easily handled while still fulfilling their functions efficiently.

To accomplish this I construct the burner as follows and as shown on the annexed drawings in which—

Figure 1 is a sectional elevation on the line *a a* of Fig. 2.

Fig. 2 a plan of a burner and housing, and

Fig. 3 a sectional elevation on an enlarged scale of the vaporizer.

I provide a cover or housing 1 of cylindrical shape, the upper part 2 preferably being of smaller diameter. The lower end 3 of said housing is open and adapted to carry a globe or shade by the screws 4 or otherwise and the top is partially closed, an opening 5 being provided for the passage of the products of combustion and also a perforation adapted to receive the end of the vaporizer hereinafter described. Directly above this perforation is fixed vertically an injector tube 6 with suitable venturi construction and lateral air inlets 7. The upper part of said injector tube is curved and connects with a tube 8 of larger section which is led into and fixed to the said housing 1 the upper end of this tube is closed and is adapted to connect the burner to its support such as by the screwed tube 9. To the lower end is attached a perforated burner head 10 for carrying the mantle.

The vaporizer, Fig. 3, together with nip-

ple containing the jet orifice and means to clear same is constructed as an independent unit and so arranged as to be easy to remove and replace.

The vaporizer consists of a tube 11 to one end of which is screwed a nipple 12 having a jet orifice. The other end has a T piece 13 attached, one arm 14 of which is attached to a union 15 for connecting the oil supply, the other arm 16 being fitted with a gland 17 through which a wire 18 is passed for clearing the jet orifice of the nipple 12 with means provided for reciprocating same, such means preferably consisting of a button 19 carried by a stem 20 which encircles a projecting sleeve 21 which passes into a casing 22 secured to the arm 16, the sleeve 21 being provided with a splayed end riding in an enlarged portion of the hole in the casing 22 to prevent the tube 21 being wholly withdrawn. A small tube 23 is placed centrally with the larger tube 11 to act as a guide for the wire 18. A wire gauze or the like may be placed in the horizontal part of vapor tube 11.

The vaporizer when in position as at Figs. 1 and 2 extends horizontally from a sufficient distance outside the housing 1 to prevent the oil being over heated in the supply pipe 15 to a point inside where it curves upward as shown and fits into the injector tube 6, a clip 24 being provided to secure it in position.

The oil supply union 15^a is provided with feathers which fit the slots 25 in the arm 14 to prevent twisting and the coned seating 26 is of small dimensions relative to the knurled cap nut 27 enabling the joint to be tightened by hand, without the aid of spanners.

The jet clearing wire 18 is operated by means of the handle or knob 19 carrying the sleeve 21 which sleeve 21 is adapted to slide in the casing 22 and the splayed end of the tube 21 and the end of the stem 20 serve to limit the range through which the wire 18 is reciprocated.

An annular spirit cup 28 having a filling nozzle 29 is provided for pre-heating the vaporizer and is suitably fitted to the housing or may be otherwise applied.

30 is a holed centering piece or spider in the nozzle 12 for centering the tube 23 the other end of which tube is held in the T piece 13 and as will be understood the oil

passes through the union 15* into the tube 11 where it is vaporized by the heat from the burner and such vapor passes through the nozzle 12 into the air mixing tube 6 and down the tube 8 to the burner 10 the heat imparted to the tube 8 supervaporizing the mixture before it reaches the burner 10.

31 is a screw engaging the stem 20 for holding the wire 18 to such stem 20.

10 What I do claim as my invention and desire to secure by Letters Patent, is:

1. In a vaporizer for vapor burners and lamps, a bent outer tube having a nozzle at one end, a smaller curved tube mounted in said outer tube, a wire extending through said inner tube adapted to engage and clean said nozzle, a casing connected to said outer tube having a recess formed therein, a handle secured to the free end of said wire for longitudinally reciprocating the latter, a sleeve having a splayed end slidably mounted in said recess and secured to said handle whereby the reciprocations of said wire in

one direction are limited by said splayed end abutting a wall of said recess and in the other direction by said handle abutting the casing.

2. In vapor burners and lamps, a housing having an air opening formed therein and a heating device forming a closure for the bottom thereof, a burner tube mounted in said housing, a vaporizer having a bent portion mounted adjacent said burner tube and in proximity to said heating device, an injector tube connecting said vaporizer and burner tube and means for supplying fuel to said vaporizer at a point outside of and spaced from said housing.

In testimony whereof I have hereunto set my hand in presence of two subscribing witnesses.

FRÉDERICK CHARLES TILLEY.
